United States Patent Office

Des. 193,547
Patented Sept. 11, 1962

193,547

MODULAR HOUSE

Emil A. Tessin II, Cuyahoga Falls, Ohio, assignor to Alside Homes Corporation, a corporation of Ohio

Filed Dec. 6, 1961, Ser. No. 67,814

Term of patent 14 years

(Cl. D13—1)

Des. 193,547

PAGE 2

FIG. 2

I claim:

The ornamental design for a modular house, as shown.
